United States Patent Office

Des. 211,544
Patented June 25, 1968

211,544

STAPLER

William Leon Gaya, Summit, N.J., assignor to The Bates Manufacturing Company, Orange, N.J., a corporation of New Jersey

Filed June 27, 1967, Ser. No. 7,613

Term of patent 14 years

(Cl. D74—1)

FIGURE 1 is a side elevation of a stapler, showing my design, the other side elevation being a mirror image thereof;

I claim:

The ornamental design for a stapler, as shown and described.
